UNITED STATES PATENT OFFICE

WALTER D. TEAGUE, OF NEW YORK, N. Y.

DESIGN FOR A CAMERA CASING

Application filed August 20, 1932. Serial No. 44,844. Term of patent 3½ years.

To all whom it may concern:

Be it known that I, WALTER D. TEAGUE, a citizen of the United States of America, residing at New York city, in the county of New York and State of New York, have invented a new, original, and ornamental Design for Camera Casings, of which the following is a specification, reference being had to the accompanying drawing, forming a part thereof.

Figure 1 is a front elevation of a camera casing showing my new design. Fig. 2 is a perspective view of the camera casing from the rear and side.

The lines in the drawing are not intended to represent color but are for the purpose of illustrating different shades or intensities of the decorative panels. The decorative panel is a metallic plate of negligible thickness.

I claim:

The ornamental design for a camera casing, substantially as shown and described.

Signed at Rochester, New York, this 29th day of July, 1932.

WALTER D. TEAGUE.
